DECK TILT COMPUTATION SYSTEM

George A. Crowther, Manhasset, N.Y., assignor to Sperry Rand Corporation, Ford Instrument Company Division, Long Island City, N.Y., a corporation of Delaware

Application February 14, 1956, Serial No. 566,067

6 Claims. (Cl. 235—61.5)

The invention relates to the art of naval gunfire control and more particularly to a method and apparatus for determining (1) the relative target bearing B_r , i.e., the angle between the vertical plane through a ship's centerline and the vertical plane through the line of sight, measured in the horizontal plane clockwise from the bow, and (2) the deck tilt correction jB_r , i.e. the change in train due to the inclination of director roller path from horizontal.

In certain types of naval gunfire controls, guns are controlled on the moving ship from a director, which measures the present position of the target in train B_r , i.e., the angle between the vertical plane through the ship's centerline and the vertical plane through the line of sight, measured in the deck plane clockwise from the bow, and which measures also the elevation E_b , i.e. the angle between the line of sight and the deck plane measured in the vertical plane through the line of sight. From this data and other data, the predicted position of the target in train and elevation at the end of the time of flight of the projectiles is computed in a computer.

On a ship, director train B_r is measured in the deck plane. Since the ship will roll and pitch, angles measured in the deck plane will vary with this movement and hence must be corrected to compensate therefor. For that reason, it is necessary to convert the data defining the target position which is observed with respect to the deck of the ship to a coordinate system with respect to the earth.

From such data as the director train B_r , the level angle L , i.e., the angle between the deck plane and the horizontal plane measured in the vertical plane through the line of sight, and the cross-level angle Z_d , i.e., the angle between the vertical plane through the line of sight and the plane perpendicular to the deck plane through the intersection of the deck plane and the vertical plane through the line of sight, the relative target bearing B_r is determined and transmitted to the computer to obtain deflection rates and other fire control quantities. From this data, there is also obtained the deck tilt correction jB_r which is transmitted to the gun director to compensate for roll and pitch, so that the director remains sighted on the target, in spite of this ship movement.

The relation of the director train B_r , the relative target bearing B_r and the deck tilt correction jB_r is $jB_r = B_r - B_r$.

In one prior art system, the deck tilt correction jB_r has been computed by using variations of the formula

$$\cot B_r = \cot B'_r (\cos L / \cos Z_d) - \sin L \tan Z_d$$

and by eliminating B_r therefrom, as was done in one case or by eliminating B'_r as was done in U.S. Patent No. 2,658,674.

In these prior art processes and systems, the deck tilt tilt correction jB_r has been obtained after obtaining the relative target bearing B_r , by subtracting the director

train B'_r from the relative target bearing B_r . The deck correction jB'_r so obtained, has been transmitted in the desired form to the director control. However, when so transmitted, the item jB'_r is subjected to perturbations in both the major angle B_r and the angle B'_r , especially in rough weather, and therefore, tends to affect adversely the stability of director control.

Also, in certain gunfire controls proposed, the apparatus for obtaining the relative target bearing B_r and the deck tilt correction jB'_r , consisted essentially of potentiometers to obtain a series of trigonometric functions. Such potentiometers being resistance types of devices, they operate through finite steps or resolutions and are subjected to heavy abrasive wear.

15 One object of the present invention is to provide a new and improved method and apparatus for computing the relative target bearing B_r and the deck tilt correction jB'_r independently, so that perturbations in B_r will not affect jB'_r .

20 Another object of the invention is to provide a new and improved method and apparatus, which computes continuously the relative target bearing B_r and the deck tilt correction jB'_r and which consists essentially of a series of electromagnetic basic resolvers and vector solvers of the type affording the advantage of high accuracy due to their infinite resolutions and of long wear due to the absence of abrasive action.

25 In accordance with certain features of the present invention, the relative target bearing B_r is obtained by solving directly for B_r in the equation

$$\sin B'_r \cos Z_d \cos B_r - (\cos B'_r \cos L - \sin B'_r \sin Z_d \sin L) \sin B_r = 0$$

30 this equation representing a true solution of the problem. This involves a solution by servo of a right triangle, the sides of which are $\sin B'_r \cos Z_d$ and

$$(\cos B'_r \cos L - \sin B'_r \sin Z_d \sin L)$$

35 and whose hypotenuse is the cosine of the angle of pitch N of the vessel. Utilizing the quantities

$$\sin B'_r \cos Z_d$$

and

$$(\cos B'_r \cos L - \sin B'_r \sin Z_d \sin L)$$

40 45 and the known angle B'_r , the sides

$$[(\cos B'_r \cos L - \sin B'_r \sin Z_d \sin L) \sin B'_r - \sin B'_r \cos Z_d \cos B'_r]$$

and

$$[(\cos B'_r \cos L - \sin B'_r \sin Z_d \sin L) \cos B'_r + \sin B'_r \cos Z_d \sin B'_r]$$

50 55 of the right triangle containing the angle jB'_r may be determined. The angle jB'_r may then be obtained by solving the equation

$$\sin jB'_r = (\cos B'_r \cos L - \sin B'_r \sin Z_d \sin L) \sin B'_r - \sin B'_r \cos Z_d \cos B'_r$$

Since the hypotenuse of this angle is the $\cos N$ as noted above, the solution will be in error by the percentage $\cos N$ differs from unity. Since the pitch of the vessel rarely exceeds 5° and the cosine of an angle so small is close to unity, this error may be ignored. However, by utilizing the customary solution by servo of a right triangle whose sides are known, the angle jB'_r may be solved with no error.

60 65 The formula which is solved for deck tilt correction jB'_r does not contain the quantity B_r , so that any perturbations in this quantity B_r does not affect adversely the accuracy of the quantities jB'_r obtained.

70 75 Various other objects, features and advantages of the present invention are apparent from the following description and from the accompanying drawings, in which

Fig. 8 is a simplified basic circuit diagram for mechanizing and solving the derived equation for the deck tilt correction jBr , using an accurate true formulation in which the departures of the cosine of the pitch angle of the vessel from unity are considered in the formulation, the full lines in said circuit indicating electrical transmission lines, while the dotted lines indicate mechanical transmission lines.

GLOSSARY

A tabulation of symbols and terms involved in the following computations and used in the drawings and in the description in connection with a ship and a gunfire control system thereon is submitted herein.

(B) True Target Bearing. The angle between true north and the vertical plane through the line of sight, measured in a horizontal plane clockwise from true north.

$$B=Co+Br$$

(Br) Relative Target Bearing. The angle between the vertical plane through the ship's centerline and the vertical plane through the line of sight, measured in the horizontal plane clockwise from the bow.

(B'r) Director Train. The angle between the vertical plane through the ship's centerline and the vertical plane through the line of sight, measured in the deck plane clockwise from the bow.

(jBr) Deck Tilt Correction. The change in train due to inclination of director roller path from horizontal

$$jBr=Br-B'r$$

(Co) Ship Course. The compass heading of the ship.

(L) Level Angle. The angle between the deck plane and the horizontal plane, measured in the vertical plane through the line of sight, this angle being considered positive when the portion of the deck toward the target is down.

(Zd) Cross-Level Angle. The angle between the vertical plane through the line of sight and the plane perpendicular to the deck plane through the intersection of the deck plane and the vertical plane through the line of sight.

FIRE CONTROL SYSTEM

The fire control system, aside from the deck tilt corrector, including the part for computing relative target bearing Br , forms no part of the present invention. A

suitable fire control system in which the deck tilt corrector of the present invention may be employed, includes in general a gun director, a stable element and a computer capable of solving gunfire control problems both anti-aircraft and surface. The deck tilt corrector of the present invention, constituting part of the computer, receives the director train $B'r$ measured in the deck plane, and receives from the stable element the level L and the cross-level Zd and computes from this data the relative target bearing Br and the deck tilt correction jBr independently of said relative target bearing.

The ship course Co from the fire control gyro compass is combined with the relative target bearing Br in an adding component to form the true target bearing B according to the relationship

$$B=Co+Br$$

This true target bearing B , as well as the relative target bearing Br are transmitted to another part of the computer to compute therefrom quantities necessary for proper firing. The ship course Co drives a generator whose output $d(Co)$, rate of change of Co , is used at the gun director as an aid in tracking. The deck tilt correction jBr derived from the deck tilt corrector of the present invention, drives another generator, whose output is $d(jBr)$, the rate of change of jBr . This quantity $d(jBr)$ is transmitted to the gun director to compensate for the roll and pitch of the ship and to aid thereby in tracking the target.

Derivation of true solution formula for relative target bearing Br and for deck tilt correction jBr

In accordance with present invention, a true solution for the deck tilt problem is employed, except that the cosine of the pitch of the ship is ignored in a specific embodiment, thereby eliminating errors, such as those which would be inherent if an empirical solution were employed. As a result of the present invention, a true solution formula is obtained containing as terms the level angle L , the cross-level angle Zd , the relative target bearing Br and the director train $B'r$. This formula is solved for the relative target bearing Br by a servo or null seeking system, which so drives the Br line that a balance is obtained between the quantities on opposite sides of the formula.

From the formula indicated, another true solution formula is derived containing the additional quantity jBr . This additional formula is solved for the deck tilt correction jBr by a servo or null seeking system, separate from that employed in obtaining the quantity Br and operating to so drive the jBr line that a balance is obtained between the quantities on opposite sides of said additional formula.

The deck tilt problem is indicated in the diagram shown in Fig. 1. This problem is solved in accordance with a true solution, using as inputs the level angle L and the cross-level angle Zd obtained from the stable element on the ship or craft carrying the fire control system, and the director train $B'r$ in the deck plane, obtained from the gun director, to derive the relative target bearing Br in the horizontal plane and the deck tilt correction jBr .

Considering the right triangle in the deck plane in Fig. 1 containing the angle $B'r$, the side Y' adjacent said angle and the side X' opposite said angle, we have

$$X'=\sin B'r \quad (1)$$

$$Y'=\cos B'r \quad (2)$$

Considering the right triangle containing the angle Zd , the side X adjacent to said angle and the side Z'' opposite said angle, we have

$$X=X' \cos Zd$$

and

$$Z''=X' \sin Zd$$

Substituting from Equation 1, we have

$$X = \sin B'r \cos Zd \quad (3)$$

$$Z'' = \sin B'r \sin Zd \quad (4)$$

Referring to Fig. 2 showing part of the diagram of Fig. 1, and considering the right triangle in Fig. 2 containing the angle L and the hypotenuse Y', and the right triangle containing the angle L and the hypotenuse Z'', we have

$$Y = Y' \cos L - Z'' \sin L$$

Substituting from Equations 2 and 4, we have

$$Y = \cos B'r \cos L - \sin B'r \sin Zd \sin L \quad (5)$$

Referring to Fig. 3, showing part of the diagram of Fig. 1, we have

$$a = Y \sin Br = X \cos Br$$

Therefore,

$$X \cos Br - Y \sin Br = 0 \quad (6)$$

Substituting into Equation 6 the value of X from Equation 3 and the value of Y from Equation 5, there is obtained

$$\sin B'r \cos Zd \cos Br - (\cos B'r \cos L - \sin B'r \sin Zd \sin L) \sin Br = 0 \quad (7)$$

Equation 7 can be solved by a servo to obtain directly the quantity Br.

To obtain the quantity jB'r, there is employed the relationship

$$jB'r = Br - B'r \quad (8)$$

It should be noted from Fig. 1, that the hypotenuse of the right triangle containing the angle Br and the sides X and Y is cos N. Referring to Fig. 4, which is partly derived from Fig. 1, it is seen that

$$d = e - f$$

$$e = Y \sin B'r$$

$$f = X \cos B'r$$

Therefore,

$$d = Y \sin B'r - X \cos B'r \quad (9)$$

Sin jB'r is proportional to or equal to d. Therefore,

$$\sin jB'r \approx Y \sin B'r - X \cos B'r$$

From Fig. 4

$$Y = \cos Br \cos N$$

$$X = \sin Br \cos N$$

Cos N is almost unity within the usual range of pitch, which is rarely above 5°. At 2 1/2° pitch, the cos N would be .999 and at 5° pitch, the cos N is .996. Therefore, for all practical purposes, cos N can be considered unity and consequently any error resulting therefrom can be ignored. Under these conditions, it can be assumed for approximation, that

$$\sin jB'r = Y \sin B'r - X \cos B'r \quad (10)$$

To determine the exact equation by which the quantity jB'r can be accurately determined, reference is again made to Fig. 4. It is found therefrom that

$$\cos N = \frac{d}{\sin jB'r}$$

Substituting the value of d from Equation 9, there is obtained

$$\cos N = \frac{Y \sin B'r - X \cos B'r}{\sin jB'r} \quad (11)$$

Also from Fig. 4

$$\cos N = \frac{g + h}{\cos jB'r}$$

$$g = Y \cos B'r$$

and

$$h = X \sin B'r$$

Therefore,

$$\cos N = \frac{Y \cos B'r + X \sin B'r}{\cos jB'r} \quad (12)$$

From Equations 11 and 12, it is seen that

$$(Y \sin B'r - X \cos B'r) \cos jB'r - (Y \cos B'r + X \sin B'r) \sin jB'r = 0 \quad (13)$$

Equation 13 is the true equation from which the deck tilt correction jB'r may be accurately determined.

Mechanism for solving equations for Br and jB'r

The mechanism for solving the equations Br and jB'r is made up of a series of components, which per se, do not constitute the subject-matter of the present invention. The equations to be solved, however, are such as to lend themselves to efficient solution by well-known components having the characteristics of affording accurate solutions and long life. Some of these components are resolver systems of the electromagnetic type and include two types referred to herein as a basic resolver and a vector solver respectively. A form of basic resolver is shown in Fig. 5 for accommodating one electrical input and one mechanical input. This basic resolver is a motor-like device resembling a two phase, two pole induction motor and consisting essentially of a stator and a rotor, each containing two distributed windings, separated 90° mechanically with respect to each other, the winding distribution being such that the mutual coupling of rotor and stator would be an exact sinusoid with rotation. The stator windings are indicated as S1-3 and S4-2 and the rotor windings R1-3 and R4-2. With the mechanical rotor input θ and electrical input E1, the outputs would be

$$Er2 = E1 \sin \theta$$

$$Er1 = E1 \cos \theta$$

Fig. 6 shows a vector solver for handling two electrical inputs and one mechanical input. The arrangement of this vector solver is somewhat similar to that of Fig. 5, except that two identical stator windings S'1-3 and S'4-2 are employed to receive two electrical inputs E'2 and E'1 respectively. The rotor is similar to that of Fig. 5, with two windings R'1-3 and R'4-2 displaced mechanically 90° apart. With the mechanical input θ and electrical inputs E'1 and E'2, the outputs would be

$$E'r2 = E'1 \sin \theta + E'2 \cos \theta$$

$$E'r1 = E'1 \cos \theta - E'2 \sin \theta$$

In both of the components of Figs. 5 and 6, a reference input voltage of constant value is applied, although not indicated in the drawings, so that the quantities computed have parametric coefficients. These parametric coefficients are a function of the reference voltage, and for the sake of simplicity will not be indicated herein after in the representation of the different quantities computed.

Fig. 7 shows a system for mechanizing and solving Equations 8 and 11 to obtain accurate values for the quantity Br and values for the quantity jB'r in which the departures of cos N from unity are ignored. In this mechanism, the director train B'r from the gun director is fed continuously as a mechanical input into a resolver 10 of the general type shown in Fig. 5, to obtain outputs sin B'r and cos B'r in the form of voltages. The electrical output sin B'r is fed into a resolver 11 of the general type shown in Fig. 5, in conjunction with the mechanical cross-level input Zd obtained from the stable element of the ship, to obtain the two output quantities sin B'r sin Zd and sin B'r cos Zd = X. The other electrical output cos B'r from the resolver 10 and the quantity sin B'r sin Zd from the resolver 11 are fed as electrical inputs into a vector solver 12 of the general type shown in Fig. 6, in conjunction with the mechanical input level L derived from the stable element of the ship, to obtain the electrical output

$$\cos B'r \cos L - \sin B'r \sin Zd \sin L = Y$$

The output Y from the resolver 12 and the output X from the resolver 11 are fed as electrical inputs into

a vector solver 13 of the general type shown in Fig. 6, in conjunction with the mechanical relative target bearing input B_r obtained from a servomechanism 14. The electrical output of the vector solver 13 is

$$X \cos B_r - Y \sin B_r$$

which corresponds to Equation 8 and which therefore is equal to zero. If the conditions of the Equation 8 are not satisfied, an error is produced at the output of the vector solver 13, which is a voltage having the proper polarity to drive the servo motor of the servo mechanism to produce a null in the error voltage. When this null is achieved, the quantity B_r converted into a mechanical quantity, such as shaft rotation, becomes the relative target bearing B_r desired. This quantity B_r is transmitted to another part of the computer (not shown) to obtain deflection rates and other fire control quantities.

A servomechanism, such as the servomechanism 14, is well-known per se, and constitutes an automatic drive which positions a mechanical load in accurate correspondence with an input, without placing an appreciable load upon this input. The basic components of the specific servomechanism illustrated in Fig. 7, comprises a servo control 15, a servo amplifier 16, a servo motor 17 and an induction generator 18 connected with a control network, which in the illustrated embodiment is the vector solver 13. Essentially, the vector solver 13 computes a voltage proportional to the error between a function of the input and a function of the output. This error voltage is converted from a high frequency, as for example, a frequency of 400 cycles as a computing reference, to a frequency of 60 cycles by the servo control 15, amplified by the servo amplifier 16 and finally supplied to the servo motor 17 for its control. The servo motor 17 furnishes the mechanical output of the servomechanism, this output being fed back into the vector solver 13 as an input and also driving the induction generator 18. From this generator 18, a voltage proportional to the output velocity is supplied to the servo control 15. This voltage modified and combined with the error voltage from the vector solver 13 in the servo control 15 improves the operation of the servomechanism.

It is seen that the relative target bearing B_r is obtained directly from Equation 8, without first obtaining the deck tilt correction jB_r and then adding this correction to the director train B_r .

The deck tilt correction jB_r is obtained independently of the quantity B_r by solving Equation 11. For that purpose, the electrical output Y from the vector solver 12 and the electrical output X from the vector solver 11 are fed as inputs into a vector solver 20 of the general type shown in Fig. 6, in conjunction with the mechanical input B_r derived from the gun director, to obtain the electrical output $X \sin B_r - X \cos B_r$. The latter quantity is fed into a summing network 21 as an electrical input. This summing network 21 may be of well-known construction, and may consist essentially of a series of resistances corresponding in number to the number of electrical inputs (in this specific case two), connected together in parallel, the different resistance ratios being selected to convert the two input voltages to a common scale, i.e., to the same value per volt. The other electrical input $\sin jB_r$ into the summing network 21 comes from a resolver 22 of the general type shown in Fig. 5 having as a mechanical input the quantity jB_r derived from the output of a servomechanism 23, similar to the servomechanism 14.

The two computing channels in the system of Fig. 7 feeding into the summing network 21 as described, produce the output quantity $Y \sin B_r - X \cos B_r - \sin jB_r$ which is equal to zero according to Equation 11. However, the error voltage from the output of the summing network 21, is fed into the servomechanism 23, 75

which nulls this error when jB_r derived as a mechanical output satisfies Equation 11.

In Fig. 8 is shown a system, in which Equation 14 is mechanized and solved to obtain the deck tilt correction jB_r accurately. In this system, the quantities X and Y are obtained as in the system of Fig. 7, but these quantities are fed as electrical inputs into a vector solver 26 of the general type shown in Fig. 6, in conjunction with the mechanical input director train B_r derived from the gun director. The electrical outputs from this vector solver 26 are $Y \sin B_r - X \cos B_r$ and $Y \cos B_r + X \sin B_r$. These outputs are fed as electrical inputs into a vector solver 27 of the general type shown in Fig. 6 in conjunction with the mechanical input jB_r derived from the output of a servomechanism 28, similar to the servomechanism 14 in Fig. 7. The electrical output of this vector solver 27 is

$$(Y \sin B_r - X \cos B_r) \cos jB_r - (Y \cos B_r + X \sin B_r) \sin jB_r$$

this output being equal to zero according to Equation 14. However, the error voltage from the output of this summing network, is fed into the servomechanism 28, 25 which nulls this error when jB_r derived as a mechanical output satisfies Equation 14.

In the systems of Figs. 7 and 8, the deck tilt correction jB_r is not derived from the relative target bearing B_r , so that this correction is not susceptible to perturbations 30 in the quantity B_r . Stability in director control is thereby maintained.

While the invention has been described with particular reference to specific embodiments, it is to be understood that it is not to be limited thereto, but is to be construed broadly and restricted solely by the scope of the appended claims.

What is claimed is:

1. An apparatus in a gunfire control for continuously producing a quantity corresponding to the relative target bearing B_r in a form for transmittal, comprising means responsive to inputs B_r and Z_d for obtaining the computed quantity $\sin B_r \cos Z_d$, wherein B_r is the director train and Z_d is the cross-level, means responsive to inputs B_r , Z_d and L for obtaining the computed quantity

$$\cos B_r \cos L - \sin B_r \sin Z_d \sin L$$

wherein L is the level, means responsive to said computed quantities and B_r as inputs for obtaining the 50 computed quantity

$$\sin B_r \cos Z_d \cos B_r - (\cos B_r \cos L - \sin B_r \sin Z_d \sin L) \sin B_r$$

and a servomechanism for nulling the latter quantity to obtain the quantity B_r .

2. An apparatus as described in claim 1, wherein the means for obtaining said computed quantities are electromagnetic motor-like resolver systems, each comprising a stator and a rotor with respective windings.

3. An apparatus in a gunfire control for continuously computing deck tilt correction jB_r and for continuously producing a quantity corresponding to said correction in transmittable form, comprising means responsive to inputs B_r and Z_d for producing the computed quantity $\cos Z_d \sin B_r$ wherein Z_d represents the cross-level and B_r represents the director train, means responsive to inputs B_r , Z_d and L for producing the computed quantity $\cos B_r \cos L - \sin B_r \sin Z_d \sin L$, wherein L represents the level, means responsive to said computed quantities and the quantity B_r as inputs for producing the computed quantity

$$\cos B_r \cos L - \sin B_r \sin Z_d \sin L$$

$$\sin B_r - \sin B_r \cos Z_d \cos B_r$$

means for algebraically adding the latter quantity to $\sin jB'r$ to produce a quantity which departs from zero by an amount constituting an error, and means for subjecting the error quantity to a null seeking operation to reduce said error to a minimum and to produce the quantity $jB'r$.

4. An apparatus as described in claim 3, wherein the means for obtaining said computed quantities are electro-magnetic motor-like resolver systems, each comprising a stator and a rotor with respective windings.

5. An apparatus in a gunfire control for continuously computing deck tilt correction $jB'r$ and for continuously producing a quantity corresponding to said correction in transmittable form, comprising means responsive to inputs $B'r$ and Zd for producing the computed quantity $\cos Zd \sin B'r$, wherein Zd represents the cross-level and $B'r$ represents the director train, means responsive to inputs $B'r$, Zd and L for producing the computed quantity $\cos B'r \cos L - \sin B'r \sin Zd \sin L$, wherein L represents the level, means responsive to said computed quantities
